UNITED STATES PATENT OFFICE.

JOHN K. STEWART, OF CHICAGO, ILLINOIS.

CLIPPER OR SHEARING-TOOL.

SPECIFICATION forming part of Letters Patent No. 698,073, dated April 22, 1902.

Application filed August 26, 1901. Serial No. 73,277. (No model.)

To all whom it may concern:

Be it known that I, JOHN K. STEWART, a citizen of the United States, residing at Chicago, in the county of Cook and State of Illinois, have invented certain new and useful Improvements in Clippers or Shearing-Tools, of which the following is a specification, reference being had to the accompanying drawings, forming a part thereof.

10 This invention relates to clippers or shearing-tools; and it consists of features of construction which are set out in the claims.

15 In the drawings, Figure 1 is a longitudinal vertical section of my improved shearing-tool. Fig. 2 is a top plan of the same with the cap-plate removed. Fig. 3 is a transverse section at the line 3 3 on Fig. 1.

A is the body on which the operating parts are journaled and mounted and which carries with it at the forward end a comb or fixed cutter.

B is the operating-shaft, journaled in the handle or body C and actuating the main lever D by the customary crank-pin and roller operating in the vertical channel D' at the rear end of the lever D. The lever D is fulcrumed on a post A³, rigid with the body A. It is bifurcated forward of its bearing on the pivot-post, and the arms D⁴ D⁴ of such bifurcation are connected at a distance back of their ends at the upper side by the cross-bar D². The inner surfaces of the arms D⁴ D⁴, facing each other, are accurately finished in parallel vertical planes, and fitting closely between them is a bushing sleeve or collar L, having its opposite vertical sides correspondingly finished to seat accurately on the facing inner surfaces of the arms D⁴ D⁴, so that said sleeve has capacity for movement with respect to the arms only in the direction of said fore-and-aft vertical planes without capacity for lateral movement with respect to said arms. In the cylindrical longitudinal aperture of the sleeve there is accurately fitted and journaled the cylindrical stem E² of a secondary lever E, said lever being spread or forked at its forward end, terminating in the bearing-fingers E' E' of the vibrating cutter G, toward the opposite end of the latter, and having just behind said bearing-fingers the pins e e, which take into the oscillating cutter, thereby constituting said secondary

lever the medium by which the operating-lever D communicates movement to the oscillating cutter.

55

H is a supplemental lever-finger which is pivoted at h to the secondary lever E and extends forward of the pivot under or in a slot or channel E⁵ of the secondary lever E, protruding between the fingers E' E' of the latter and bearing upon the middle tooth G² of the cutter G.

H' is a pivot-bolt which is set through one of the fork-arms D⁴ and screwed into the other fork-arm, having its head or shoulder H¹⁰ bearing upon the arm through which it is inserted, whereby it is adapted to crowd said arms together slightly, taking advantage of the spring of the metal to insure a perfectly close fit of the bushing-sleeve between 70 said arms, while at the same time permitting said sleeve sufficient freedom for the movement which it may require in the plane of the parallel faces of the sleeve and said arm.

This pivot-pin taking through the sleeve, 75 which is slotted vertically at l l for that purpose, in like manner takes through the stem E² of the secondary lever E, the aperture e² being also slightly elongated vertically to permit slight vertical movement of the lever with respect to the pivot-bolt. This bolt is the pivot-bearing of the supplemental lever-finger H, which is thus directly pivoted to the operating-lever D; but the pivot-aperture in said supplemental lever-finger H is 80 slightly larger than the pivot to permit slight oscillation of said finger, and thereby of the secondary lever E, in the channel of which said finger is confined, and the said finger and said secondary lever are thus made capable 85 of pivotal action in vertical plane and slight oscillatory action about the stem of the said secondary lever. It will be seen that the secondary lever by its close fit in the bushing-sleeve and by the close fit of that sleeve between the fork-arms D⁴ D⁴ of the operating-lever D is insured full range of movement 95 about the fulcrum-post A³ and is thereby adapted to give full cutting movement to the vibrating cutter G, while at the same time, 100 by reason of the construction described permitting a rocking or oscillation of the secondary lever about the axis of its stem, the lever E is adapted to accommodate itself per-

fectly to the slightest inaccuracy which may exist in the construction, which might cause the vibrating cutter to bind or press more forcibly upon the fixed comb or cutter at one part of its path than at another, and this is the purpose of the construction described, considered generally, while specifically the purpose of the bushing-sleeve is to prevent lost motion or wear which might occur between the secondary lever and the main operating-lever in respect to the cutting movement, the broad surfaces of the bushing-sleeve where it bears upon the inner surfaces of the fork-arms D^4 of the operating lever and the provision of the pivot-bolt H' , adapted to clamp said arms on the sleeve, being a complete safeguard against any lost motion at this point, while the extended surface of the cylindrical stem E^2 , bearing within the bushing, and the very slight range of oscillation which occurs at these bearing-surfaces insure freedom from lost motion at this point.

A' is a cap which constitutes the upper part of the case A and closes it above. J is a steel plate which closes an aperture in the cap-plate above the cross-bar D^2 , said plate being held to the cap by bolts j , which also hold the cap to the main body or case A . The under surface of the plate J is parallel to the plane of contact of the cutters, and the upper face of the cross-bar D^2 is designed to be also in that plane, and its face bears on the under surface of the plate J as the operating-lever vibrates. In order to lubricate the surfaces of the plate J and cross-bar D^2 , which are in rubbing contact during the action of the machine, the plate J has an aperture J^{10} , in which is inserted a thimble or cup J' , filled with fibrous absorbent material M , as felt, adapted to absorb and retain and particularly to strain the oil for lubricating said surfaces. This thimble is represented as spun with retaining-flanges at the upper and lower edges and a shoulder M' , stopping it on the plate J , so that the lower end shall not touch the bar D^2 , the felt M being protruded sufficiently to carry the oil to the surface of said bar.

F is the screw for adjusting the pressure of the oscillating cutter upon the fixed comb or cutter. To accommodate it, the operating-lever D has a vertically-extending boss D^5 , hollow from top to bottom and interiorly threaded. Into the threaded aperture of this boss, at the forward side, an opening D^{50} leads from the space between the fork-arms D^4 D^4 , and the rear end of the secondary lever E protrudes through this opening into the vertical cavity provided for the adjusting-screw F , and said screw at an intermediate portion of its length has a circumferentially-extending or annular groove F' , (interrupting the thread at that part,) into which the rear end of said secondary lever E takes, so that as the screw is operated up and down by rotation the said rear end of the secondary lever is similarly carried up and down and the forward end is

pressed more or less forcibly upon the cutter G .

I claim—

1. In a clipper or shearing-tool, in combination with the vibrating cutter a main operating-lever and means for actuating it; a sleeve or collar pivoted to said main operating-lever, and a secondary lever journaled in said sleeve or collar and adapted to oscillate therein about the longitudinal axis thereof, and engaging and vibrating the cutter. 70

2. In a clipper or shearing-tool, in combination with the vibrating cutter a main operating-lever and means for actuating it; a secondary lever actuated by said main operating-lever, having pivotal connections therewith and a limited range of oscillation about a longitudinal axis, and of vertical movement 85 with respect to said main operating-lever; the latter having a recess at its forward part with parallel vertical sides, and a bushing-sleeve having corresponding parallel vertical sides fitting closely between the vertical sides of 90 said recess, said secondary lever being journaled and adapted to oscillate about the longitudinal axis of its stem in said bushing-sleeve.

3. In a clipper or shearing-tool, in combination with a vibrating cutter, the main operating-lever and means for actuating it; a secondary lever having pivotal connections with said main lever, with limited freedom of oscillation about a longitudinal axis, and of 100 vertical movement in respect to said main lever, said secondary lever bearing on the vibrating cutter and constituting the medium by which the main lever actuates said cutter; a bushing-sleeve carried by the main operating-lever and having vertical movement with respect thereto, and restrained with respect to transverse movement; the secondary lever having a cylindrical stem journaled in the bushing-sleeve and adapted to oscillate therein; and a screw operating between said main lever and said secondary lever to adjust the secondary lever in vertical plane about its pivotal connection to the main operating-lever. 110

4. In a clipper or shearing-tool, in combination with the case or body having at the forward end the comb or fixed cutter, the vibrating cutter, the main operating-lever and means for actuating it; a secondary lever which at its forward end bears upon the vibrating cutter toward the opposite end of the latter; a supplemental finger pivoted at its rear end to said secondary lever, and at its forward end bearing upon the vibrating cutter intermediate the ends of the latter, and being forward of its pivotal connection to the secondary lever pivoted also to the main operating-lever, and having at its last-mentioned pivot limited freedom of oscillation about a 125 longitudinal axis, and a bushing-sleeve on the stem of said secondary lever in which the latter is adapted to oscillate, said bushing-sleeve being mounted in the main operating-lever 130

with capacity for vertical movement but restrained against lateral movement with respect to said oscillating lever; and an adjusting-screw operating between the rear portion 5 of said secondary lever and the operating-lever, to press the forward end of the secondary lever on the vibrating cutter.

5. In a clipper or shearing-tool, in combination with a cutter-operating lever, having an upwardly-facing bearing-surface, a plate 10 against which said surface is pressed, having an aperture, and the oil holder and strainer, M, in said aperture having a flange at the upper end to retain the oil-straining material, 15 and a shoulder, M', stopping it on the plate.

6. In a clipper or shearing-tool, in combination with the cutter the main operating-lever and means for actuating it; a secondary lever actuated by said main operating-lever, 20 and having a cylindrical stem; a bushing-sleeve on such stem, lodged in the main operating-lever and having capacity for vertical movement, but restrained against lateral movement in respect thereto; a pivot-pin extending through said bushing-sleeve and 25 through said secondary lever and secured in the operating-lever, and connecting said three parts together; the aperture for said pin through the bushing-sleeve and through the 30 secondary lever being vertically elongated to afford limited range of vertical movement and

of oscillation about the axis of its stem to said secondary lever.

7. In a clipper or shearing-tool, an operating-lever and a secondary lever pivotally connected thereto, arranged at its forward end to bear upon the cutter; said operating-lever having a vertical threaded aperture back of the pivot of the secondary lever thereto and an opening into said threaded aperture at the 40 forward side, the rear end of the secondary lever extending through said opening; a screw extending in said threaded aperture, and having at an intermediate point of its threaded extent a circumferential or annular groove 45 which corresponds in position, when the screw is in operative relation with the other parts, with the opening in the forward side of said threaded aperture, the rear end of the secondary lever taking through said opening 50 and engaging in the annular groove of the screw; whereby the latter serves to elevate the rear end of the lever to cause it to press at the forward end on the cutter.

In testimony whereof I have hereunto set 55 my hand, at Chicago, Illinois, this 14th day of August, 1901.

JOHN K. STEWART.
